JACOB P. BERTRAM AND ABRAHAM BERLINER, OF ROCHESTER, NEW YORK, ASSIGNEES
TO SHURON OPTICAL COMPANY, INC., OF GENEVA, NEW YORK, A CORPORATION OF
NEW YORK

DISPLAY CASE

Application filed November 22, 1928. Serial No. 321,127.

This invention relates to a display case and has for its purpose to afford a construction that will hold one or more spectacles securely without danger of damage or breakage while 5 at the same time permitting an attractive display of the design and various parts of the spectacles.

More particularly, the invention has for its purpose to afford a simply constructed display 10 case in which spectacles can be quickly and readily positioned, and as easily removed when desired.

Another object of the invention is to afford means for supporting the different parts of a 15 spectacle frame in such a way as to securely hold the spectacle against accidental dislodgement, while giving, when the case is open, a practically unobstructed view of the lenses, lens frames, and temples of the spectacles.

With these ends in view, the invention consists in the structure and arrangement that will appear from the following description when read in conjunction with the accompanying 25 drawings, the novel features being pointed out in the claim following the description.

In the drawings:

Figure 1 is a perspective view of a display 30 case in closed position, incorporating the invention;

Figure 2 is an end view showing the case partially opened;

Figure 3 is a view similar to Figure 2 with 35 the separable sections closed, and the securing flap unfastened;

Figure 4 is a similar view with the securing flap fastened;

Figure 5 is a plan view of the case in open 40 position, and showing the cover portion thrown back, with several spectacles in position in the case.

Figure 6 is a sectional view on line 6—6 of Figure 5;

Figure 7 is a sectional view on line 7—7 of 45 Figure 5, and

Figure 8 is an enlarged sectional view on line 8—8 of Figure 5.

The invention is illustrated as embodied in 50 a display case comprising two sections 1 and

2 which are suitably hinged together and adapted to be folded together as shown in Figure 1. The case is held closed by a flap 3 carried by the section 1 provided with snap fasteners 4 engageable with the cooperating 55 fastening elements 5 on section 2. Each section of the case is also provided with a cover portion 6 of velvet or other suitable material to cover the spectacles when the case is closed and adapted to be thrown back as shown at 60 the right of Figure 5 when desired to display the spectacles in the case or remove them from the case.

Each case section 1 and 2 has a series of 65 spectacle compartments, each compartment including a pocket or recess 10 that is preferably formed by upstanding side and end walls constructed of glued cardboard laminations or constructed of other suitable material, although it will be understood that the pocket 70 in which the spectacle is mounted may be otherwise formed.

Each pocket is provided along its upper 75 side with lens supporting means preferably including a ledge or wall 11 of glued cardboard laminations or other material, and on top of the wall 11 is a tufted velvet covered pad or cushion 12 secured in place by glue or otherwise, and acting to support the lenses and spectacle frame at one side. 13 is a retaining member consisting of a metal finger or of other suitable form that may be carried by the wall 11 to extend laterally therefrom as shown in Figure 7 and engage over the central or body portions of the spectacle 85 temples, as shown in Figure 5.

The spectacle recess or pocket is formed along its other side by a similar upstanding wall 14 and a velvet covered tufted pad or cushion 15 which overlies and is attached to the wall 14. The pad 15 extends laterally beyond the wall 14, affording a shoulder 16 extending over the pocket and adapted to overlie the end portions of the spectacle temples and prevent the latter from slipping outwardly of the pocket, see Figure 7. At the ends, each pocket is provided with upstanding portions 17 also formed of cardboard laminations or other suitable material, and curved as illustrated at 18 to conform gen- 95 100

erally to the curvature of the frame and temples when folded.

To position a spectacle in the case, the temples are first folded, and the ends of the temples inserted under the shoulder 16 after which the frame as a whole is moved toward the shoulder 16, compressing the temples, and forced downwardly until the main or body portions of the temples slip under the retaining member or finger 13. The spectacle then assumes substantially the position shown in Figure 5, with the upper portions of the lenses and spectacle frame resting on the cushion 12. The retaining member 13 and ledge or shoulder 16 effectually prevent outward movement or accidental displacement of the spectacle.

To remove the spectacle, it is first forced laterally of the pocket toward the shoulder 16 until the body portions of the temples are free of the retaining member 13, and the spectacles can then be readily lifted from the pocket.

While the construction has been described with reference to a particular embodiment, it is not confined to the details herein disclosed, and this application is intended to cover such changes or modifications as may come within the intent of the improvement or the scope of the following claim.

We claim:

A spectacle case having a pocket comprising side and end walls, cushioned lens-supporting means at one side of the pocket on which the lenses are adapted to rest, a shoulder at the opposite side of the pocket affording means for engaging the ends of the temples to prevent their slipping upwardly, and a retaining device arranged below the lens-supporting means acting to overlie the body portions of the temples and to thereby retain the lenses against said supporting means.

In witness whereof, we have hereunto signed our names.

45 JACOB P. BERTRAM.
ABRAHAM BERLINER.
